(57) **CLAIM**

The ornamental design for a stand and/or support for planar or tablet computing device, as shown and described.

DESCRIPTION

FIG. 1 is a perspective view of a first embodiment of a stand and/or support for planar or tablet computing device showing my new design;

FIG. 2 is a top plan view thereof;

FIG. 3 is a bottom plan view thereof;

FIG. 4 is a front elevational view thereof;

FIG. 5 is a rear elevational view thereof;

FIG. 6 is a left elevational view thereof; and,

FIG. 7 is a right elevational view thereof.
